SELF-LEVELING DISPENSER

Thormod Jensen, Laurelton, N. Y., assignor to
American Machine and Foundry Company, a
corporation of New Jersey

Application March 31, 1948, Serial No. 18,112

6 Claims. (Cl. 312—71)

1

This invention relates to storing and dispensing apparatus of the self-leveling type such as shown in U. S. Patent 2,251,874, granted to William J. Gibbs on August 5th, 1941, and more particularly to providing ways and means for varying the capacity of self-leveling dispensers of this general class to carry loads of different weight at different times.

The capacity of present day self-leveling dispensers is changed by hooking or unhooking springs until the required number of springs are found necessary to counterbalance the material being handled. Since each spring has a predetermined rating measured in pounds per inch of travel, when the capacity of the dispenser is changed by unhooking individual springs it will necessarily have to be in multiples of a predetermined number of pounds. For example if each spring in a dispenser requires an initial pull of 15 pounds to elongate the spring one inch the capacity of the dispenser has to be changed in multiples of 15 pounds because each unhooked spring represents a 15 pound differential.

Changing the capacity of the dispenser by hooking and unhooking springs had the disadvantage that this could not be readily done when the dispenser had a substantial load because the springs would then be in an extended condition in supporting the load.

It is therefore an object of this invention to provide a device for varying the capacity of the dispenser which can be readily operated regardless of whether the dispenser is fully loaded, partially loaded or empty.

A further object is to provide a device for varying the capacity of a self leveling dispenser which an inexperienced person can quickly operate without requiring any special skill.

Another object is to provide a device which will infinitely vary the capacity of a self-leveling dispenser to enable it to carry material of different weight at different times.

Another object is to provide a device for changing the carrying capacity of a self-leveling dispenser wherein the amount of change will not be restricted to the weight carrying capacity of the individual springs used in the dispenser.

A further object is to provide a device which will enable the spring tension to be increased when a dispenser is fully loaded to overcome any friction between the material stored and the material supports surrounding the path of travel of the material carrying platform.

Another object is to provide mechanism for changing the modulus of resistance to motion

2

of the material carrying platform of a self-leveling storing and dispensing apparatus while maintaining the modulus of elasticity of springs constant.

5 A further object is to provide a lever mechanism for interconnecting the springs of a self-leveling storing and dispensing apparatus which will enable the mechanical advantage thereof to be varied to change the capacity of the apparatus.

Other objects and features of the invention will appear as the description of the particular physical embodiment selected to illustrate the invention progresses. In the accompanying drawings, 15 which form a part of this specification, like characters of reference have been applied to corresponding parts throughout the several views which make up the drawings.

Fig. 1 is a side view of a self-leveling storing 20 and dispensing apparatus taken on the line 1—1 of Fig. 4 illustrating the mechanism used for changing the capacity of the dispenser.

Fig. 2 shows the control knob for changing the 25 capacity of the self-leveling dispenser taken on line 2—2 of Fig. 1.

Fig. 3 shows a top view of the mechanism for changing the capacity of the self-leveling dispenser taken on line 3—3 of Fig. 1.

Fig. 4 shows an end view of the mechanism for 30 changing the capacity of the self-leveling dispenser taken on line 4—4 of Fig. 1.

This invention relates to the class of self-leveling dispensers such as shown in the Gibbs Patent 2,251,874, referred to above. The dispenser consists of an enclosure of housing having side walls 10, 12, 14 and 16 (Figs. 1 and 3). The lower part of side walls 10, 12, 14 and 16 35 are attached to a suitable base 18 which may be mounted on conventional swivel casters 20 to render the storage and dispensing unit readily movable.

The upper surface 22 of the dispenser is provided with a suitable opening 24 connecting with the inner shell 25 in which a table or material carrying platform 26 is raised and lowered.

The vertical path of travel of the platform carrier 26 is surrounded by an inner shell 25 similar to that shown in copending application of Christopher Bockius, S. N. 736,479, filed 40 March 22, 1947.

Bolts 28 are attached to the underside of the carrier platform 26 by suitable means such as welding and have adjustably connected thereto at their lower ends brackets 30 by means of nuts 45 32. Brackets 30 in supporting the platform 26

travel up and down in narrow slots 31 formed in the inner shell 25.

Elongated flexible members such as sprocket chains 34, 36, 38 and 40 are connected at one end to the brackets 39 and are trained over pulleys or sprockets 41, 42, 44, 46 and 48 respectively and under sprockets 50, 52, 54 and 56 and are adjustably connected at their other end to the brackets 58 which are attached to the upper portion of the housing 22. Sprockets 41 are mounted in suitable bearings attached to the side walls 14 and 16. Sprockets 42, 44, 46 and 48 are fixedly connected to the shaft 60 which is rotatably supported at opposite ends in the bearings 62 and 64 which are attached to the side walls 14 and 16.

The sprockets 50, 52, 54, and 56 are mounted on the saddle shaft 66. Bracket connections 68 and 70 are loosely mounted on the saddle shaft 66 and are held in position by suitable collars 72 and 74 which are fixed to the saddle shaft 66. Suitable cables 76 and 78 are connected at one end to the brackets 68 and 70 respectively and are wound up at their other end on suitable cable drums 80 and 82 respectively. The cable drums 80 and 82 are fixedly mounted on a shaft 84 which is rotatably supported at its opposite ends in suitable bearings 86 and 88 attached to the side walls 14 and 16.

The shaft 84 has a pinion 90 fixedly mounted thereon meshing with a gear segment 92 which is fixedly mounted on a shaft 94. Shaft 94 is rotatably supported at opposite ends in a suitable bracket 96 mounted on the base 18 and is held in place by means of a collar 98 which is also fixedly mounted on shaft 94. A pair of lugs 100 and 102 are attached to one side of the gear segment 92 and support a screw 104 at opposite ends. One end of the screw 104 projects through the lug 100 and carries a bevel gear 106 which meshes with a second bevel gear 108.

The bevel gear 108 is fixedly mounted on the end of a shaft 110 which is freely mounted in the collar 98. A splined shaft 112 slidably engaging with a sleeve 113 is provided with universal joints 114 and 116 thereby yieldably interconnecting shaft 110 with shaft 118. The shaft 118 is supported in a suitable bearing of bracket 128 attached to the side wall 16 and has fixedly mounted thereon a bevel gear 122.

Bevel gear 122 meshes with a bevel gear 124 fixedly mounted on the shaft 126. The shaft 126 is rotatably supported at opposite ends in brackets 128 and 130. The upper end of shaft 126 (Fig. 1) has a bevel gear 132 fixedly mounted thereon. The bevel gear 132 meshes with another bevel gear 134 which is fixedly mounted on a shaft 136. The shaft 136 is rotatably supported in a suitable bearing 138 mounted on the side wall 10 and has an adjusting knob 140 fixedly mounted on the end projecting outside the housing 10.

A scale 142 is attached to the housing 10. A pointer 144 mounted on the knob 140 indicates which way to turn the knob to raise or lower the level of the material on platform 26 to properly counterbalance it with the type of load being supported.

A block 146 is threaded on the screw 104 and is prevented from rotating by means of a stationary guide 148 which is connected at opposite ends to the lugs 100 and 102 (Fig. 1). By rotating the knob 140 it will cause the screw 104 to rotate, thus moving the block 146 along the length of the axis of screw 104 and thereby

change the mechanical advantage of the lever mechanism that the screw 104 forms a part of.

An anchor 152 is connected to a stud 150 which projects from the block 146. Cable 154, which is connected at one end to the anchor 152, travels around the pulley 156 and is connected at its opposite end to a suitable anchor 158 mounted on the shaft 160. Shaft 160 is fixedly connected at its opposite ends to the side walls 14 and 16 of the dispensing apparatus.

The pulley 156 is freely mounted on a stud 162 which is supported at opposite ends in the yoke 164. Yoke 164 is connected by means of cable 166 to a floating shaft 168. The shaft 168 carries at opposite ends suitable connectors 170 and 172 which are attached to the ends of sprocket chains 174 and 176 respectively. The sprocket chains 174 and 176 are trained around the sprockets 180 and 182 freely mounted in suitable bearings attached to the side walls 14 and 16.

The opposite end of sprocket chains 174 and 176 are attached to a second saddle shaft 184 which is supported in the lower hooks 186 of calibrated tension springs 188. The calibrated tension springs are of such design that they expand and contract at a uniform rate corresponding to the force of distortion exerted on the springs.

The upper end 190 of calibrated tension springs 188 is attached to adjustable hooks 192. The side wall 12 (Fig. 1) is provided with a door 194 having a hinge 196 to allow the operating mechanism of the dispensing apparatus to be readily accessible.

The operation of my invention may be briefly described as follows:

When the storage and dispensing apparatus assembled suitable adjustments are made by means of nuts 32 so that the table 26 is supported in a horizontal position by all four sprocket chains 34, 36, 38 and 40. The sprocket chains 34, 36, 38 and 40 are interconnected for equal movement with one another through the shaft 60 on which the sprockets 42, 44, 46, and 48 are fixedly mounted. Therefore when the shaft 60 is rotated all four chains will have to move an equal distance in the same direction.

The opposite ends of sprocket chains 34, 36, 38 and 40 are adjusted by means of anchor bolts 59 to equalize the length of the chains so that they all assist in supporting the saddle shaft 66. The hooks 192 (shown in Fig. 1) are similarly adjusted so that all of the springs 188 apply approximately the same amount of support to the second saddle shaft 184.

The height of the material extending above the top 22 of the dispenser is sometimes referred to as a "head load." The extent to which the "head load" builds up before the platform 26 begins to descend, depends upon the adjustment of the counter-balance of the table platform 26 as well as the weight and shape of the material being handled. When the counterbalance is properly adjusted it allows a headload to be built up to a predetermined height above the top of the dispenser, before the platform begins to descend due to additional material being stacked on the platform.

The yieldability of platform 26 is controlled by the amount of force applied to the saddle shaft 66 through cables 76 and 78. Heretofore the yieldability or material handling capacity of the platform 26 has been varied or changed by either adding or removing springs to or from the total number of active springs exerting force on the saddle shaft 66.

In the present invention it is no longer necessary to either hook or unhook springs to obtain the amount of force desired to counterbalance the weight of material being handled. Instead one merely has to turn the control knob 140 until the required amount of tension is obtained to properly counterbalance the material supported on the platform.

As the knob 140 is turned it causes the splined shaft 112 to be rotated through the connecting shaft 126. The rotation of the splined shaft 112 causes the bevel gear 108 to rotate the bevel gear 106. The rotation of the bevel gear 106 turns the screw 104 which causes the block 146 to travel along the length of the screw 104.

The screw 104 together with block 146 attached to the gear segment 92 is for all practical purposes a lever system. By moving the block 146 along the screw 104 the effective force exerted by the saddle shaft 65 and the springs 188 on each other through the lever system is proportionately varied. In the arrangement shown in Fig. 1 the cable 154 exerts a force on the screw 104 in a direction substantially at right angles thereto.

When the knob 140 is turned so that the block 146 is closely adjacent to the bracket 102 the table 26 will be the least yieldable and the springs 188 will be transmitting the greatest amount of tension to the table. When the knob 140 is turned in the opposite direction to bring the block 146 closely adjacent to the bracket 103 the table platform 26 will be the most yieldable and the springs 188 will exert the least amount of tension on the table. As the block 146 travels from one extreme position to the other along the screw 104 the sensitivity of the table 26 is gradually changed without the requiring of any of the springs 188 to be unhooked.

The table platform 26 and the inner shell 25 is of a construction similar to that shown in the copending application of Christopher Bockius, S. N. 736,479, filed March 22, 1947, which permits this apparatus to be used for supporting not only tote boxes and material of uniform weight and thickness which is capable of being stacked but also material in bulk which will be supported in part by the inner shell 25 and the platform 26.

When bulk material is stored in the dispenser it is sometimes found that the bulk material exerts a lesser pressure or wedging effect upon the inner shell 25 when the material travels downwardly on being loaded onto the platform, than when the dispenser is being unloaded and the material is lifted upwardly by the platform 26.

Therefore while the counterbalancing of the table platform 26 with the springs 188 is adequate and satisfactory when the table is in the process of being lowered it is not satisfactory when the table is in the process of being raised due to the added friction. In my present invention this problem is solved by turning the knob 140 to increase the tension exerted on the table 26 an amount sufficient to overcome the increased friction between the inner shell 25 and the material as the table 26 is raised.

The invention above described may be varied in construction within the scope of the claims, for the particular device selected to illustrate the invention is but one of many possible embodiments of the same. The invention, therefore, is not to be restricted to the precise details of the structure shown and described.

What is claimed is:

1. Storing and dispensing apparatus of the type wherein material is freely supported on a platform which is balanced to maintain the upper part of the material supported thereon at a constant predetermined level with respect to the top of said apparatus comprising, a framework, elongated flexible members trained over suitable guiding members at the top of said framework and connected at one end to said platform, a device taking up or letting out said elongated members as said platform is raised or lowered in said framework, a crank arm pivotally connected to said framework, spring tension means connected at one end to said framework and at the other end to a connection on said crank arm, means for moving said connection along the length of said arm to vary the force exerted by said spring tension means on said device, and mechanism for interconnecting the crank arm with said device to cause the crank arm and said device to move distances proportional to each other.

2. Storing and dispensing apparatus of the general type wherein material is counterbalanced by means of springs to maintain the top thereof at a constant predetermined level comprising, a material supporting platform, flexible members for lowering and raising said platform, a shaft having means for winding and unwinding said flexible members thereon, a lever arm adapted to be swung in an arc, mechanism interconnecting said arm with said shaft to move said arm and rotate said shaft distances proportional to each other, a slide movable along said lever arm, springs constructed and arranged for storing and releasing energy at a uniform rate corresponding directly with the amount of movement of said springs, means for connecting one end of said springs to said dispensing apparatus and the other end of said springs to said slide, and a knob for moving said slide along said lever arm to regulate the amount of force exerted by said springs to counterbalance material supported on said platform and thereby maintain the top of the material supported on said platform at a constant predetermined level.

3. A self leveling material storing and dispensing apparatus comprising, a housing, a table adapted and arranged to have free vertical movement within said housing, elongated flexible members for lowering and raising said table, means for actuating said elongated flexible members to raise and lower said table, said actuating means including, a drum for winding up and unwinding said elongated flexible members to raise and lower said table, a gear for rotating said drum, a gear segment for actuating said gear, a lever arm associated with said gear segment, a connection adapted and arranged to be moved along the length of said lever arm, and a calibrated spring connected at one end to said housing and at the other end to the connection mounted on said lever arm to thereby exert a force on said gear segment varying directly with the position of said connection on said lever arm.

4. A self leveling material storing and dispensing apparatus comprising, a housing, a table reciprocable vertically within said housing for supporting material so that the top of the material is maintained at a predetermined level with respect to the top of said housing, sprocket chains from which said table is suspended, a rotary member associated with said sprocket chains for lowering and raising said table, a lever arm in-

terconnected with said rotary member for movement therewith, calibrated springs anchored at one end to said housing and connected at the other end to a movable connection mounted on said lever arm, and means for moving said movable connection, along the length of said lever arm to change the amount of force exerted by said rotary member on said sprocket chains for counterbalancing material supported on said table and maintaining the top of said material at a constant predetermined level.

5. A storing and dispensing apparatus of the self leveling type comprising, a housing, a movable platform for supporting material stored in said apparatus, elongated flexible members connected at one end to said platform, a plurality of pulleys over which said elongated flexible members pass, anchors for connecting the other end of said elongated flexible members to said housing, a saddle shaft supported by a loop formed in said elongated flexible members between said anchors and said pulleys, a drum having means connected to said saddle shaft for lowering and raising said platform to counterbalance the weight of materials supported thereon and automatically maintain the top of the material at a constant predetermined level, a gear segment interconnected with said drum, an arm joined for movement with said gear segment and extending radially from the point about which the gear segment rotates, a block movable along the length of said arm, calibrated spring tension means connected to said block so that the pulling force exerted thereon will be along a path substantially in line with the 35

5 said elongated flexible members.

10 6. A self leveling storing and dispensing apparatus comprising, a vertically movable carrier platform, calibrated springs for counterbalancing said platform to maintain the top of the material supported on the platform at substantially the same level regardless of whether material is added or removed from the material already supported on the platform, a pivoted lever having input and output connections, flexible members 15 interconnecting said springs with one of the connections of said lever, a second set of flexible members interconnecting said carrier platform with the other of said connections of said lever and means for moving one of said connections toward and away from the pivot of said lever to change the output force of said lever and thereby change the load carrying capacity of said carrier platform.
